(57) **CLAIM**

We claim the ornamental design for a razor cartridge, as shown and described.

DESCRIPTION

FIG. 1 is a perspective view of the razor cartridge of the present invention.

FIG. 2 is a front elevation of the razor cartridge of FIG. 1.

FIG. 3 is a rear elevation of the razor cartridge of FIG. 1.

FIG. 4 is a left side elevation of the razor cartridge of FIG. 1.

FIG. 5 is a right side elevation of the razor cartridge of FIG. 1.

FIG. 6 is a top plan view of the razor cartridge of FIG. 1; and,

FIG. 7 is a bottom plan view of the razor cartridge of FIG. 1.

The broken line handle illustrates the environment. The remaining broken lines illustrate portions of the cartridge. None of the broken lines form part of the claimed design. The trademark "H" appearing in the drawings is a trademark of Harry's, Inc., the owner of the claimed design.
